UNITED STATES PATENT OFFICE.

JOSEPH BRADDOCK, WILLIAM B. PACK, AND WILLIAM JEFFS, OF CHILLICOTHE, OHIO.

FLY-BRUSH.

SPECIFICATION forming part of Letters Patent No. 236,928, dated January 25, 1881.

Application filed July 29, 1880. (No model.)

To all whom it may concern:

Be it known that we, JOS. BRADDOCK, WM. BAILEY PACK, and WM. JEFFS, of Chillicothe, in the county of Ross and State of Ohio, have invented certain new and useful Improvements in Fly-Brushes; and we do hereby declare the following to be a full, clear, and exact description of the invention, such as will enable others skilled in the art to 5 know which it pertains to make and use it, reference being had to the accompanying drawings, which form part of this specification.

Our invention relates to an improvement in fly-brushes; and it consists in providing each 15 one of the rods to which the brushes are attached with a counter-weight at its upper end, whereby the brush is made to operate more easily.

It further consists in making a slot through 20 the supporting-arm in which the brush is held, and providing the rod with needle-points for pivots, which pivots have their bearing in set-screws which are passed through the side of the arm.

25 It further consists in the arrangement and combination of parts, which will be more fully described hereinafter, whereby a very cheap, simple, and effective fly-brush is produced.

The object of our invention is to produce a 30 fly-brush which can be raised and lowered and attached to a table or placed beside a bed, and in which the brushes are operated by a clock-work or other suitable motive power, so that its action will be automatic.

35 Figure 1 is a side elevation of our invention, partly in section. Fig. 2 is a vertical section through the supporting-arm. Fig. 3 is a plan view of the supporting-arm. Fig. 4 shows an extension placed on the arm for the 40 purpose of operating two brushes at once. Fig. 5 is an end view of the operating mechanism.

A represents a suitable hollow stand, which is provided with suitable supporting-legs B. 45 Passing down through the top of this hollow stand A is the supporting standard or rod C, which can be vertically adjusted for the purpose of raising or lowering the brushes, and held in any desired position by means

of the set-screw N. This standard A can be 50 attached to the edge of a table by means of a set-screw, or can be placed beside a bed or any other object from which it is desired to drive away the flies.

Secured to the top of the supporting-stand 55 arm C is a suitable arm, M, which has a case, E, containing the operating mechanism, secured upon its top. This operating mechanism consists of three or more wheels, which are operated by means of a spring, and the 60 last one of the series of wheels meshes with an endless screw which has a crank, H, secured to its outer end, and which projects through the side of the case. To this crank is secured a connecting-rod, L, which unites 65 the crank to the rod O, which is pivoted in the arm M, and has the brush R secured to its lower end. This rod R passes through the slot S that is made in the arm M, and is provided with needle-points which form the pivots upon which the rod rocks. Passed through the sides of the arm are suitable adjusting-screws X, which have their ends recessed so 70 as to receive the ends of the pivot of the rod, and by means of which screws all wear can be 75 taken up at any time. Attached to the upper end of this rod O is a suitable adjustable counter-weight, Y, which causes the rod O to operate much more easily.

When it is desired to operate more than one 80 brush at a time—as, for instance, when the table is of considerable length—an additional arm, V, which has a slide secured to its inner end to fit over the outer end of the arm M, is used. This arm V having been adjusted 85 into position, and carrying a second rod, O, is then united to the first rod by means of a wire, rod, or other suitable connecting device, and then when the first rod is put in motion, by means of the spring mechanism, the sec- 90 ond rod and brush will be operated at the same time. The number of rods used, of course, can be increased to any desired extent.

By making a hollow stand, as here shown, to support the entire operating mechanism, the 95 brushes can be adjusted up and down at will, and the brush can be moved around so as to be used in any part of the house, and is a

great improvement over all those brushes which have to be suspended from the ceiling, and hence can only be used in one place.

Having thus described our invention, we 5 claim—

1. The combination of the hollow standard A, provided with legs B, with the adjustable standard C, and operating mechanism E, a supporting-arm M, and the brush-rod O, the 10 parts being arranged to operate substantially as described.
2. The arm M, secured to the top of the adjustable standard C, and having the slot S made through it, in combination with the rod 15 O, provided with needle-point pivots, and the adjusting set-screws for supporting the rod, substantially as shown and described.

3. In a fly-brush, the combination of a train of wheels, an endless screw provided with a crank, H, on its outer end, a connecting-rod, 20 L, a pivoted rod, O, having a fly-brush secured to its lower end and a counter-weight to its upper end, substantially as specified.

In testimony that we claim the foregoing we have hereunto set our hands this 14th day of 25 July, 1880.

JOSEPH BRADDOCK.
